UNITED STATES PATENT OFFICE.

WILSON E. SYMONS, OF CHICAGO, ILLINOIS.

STEEL ROOF FOR FREIGHT-CARS.

1,157,339.

Specification of Letters Patent.

Patented Oct. 19, 1915.

Application filed September 14, 1910. Serial No. 582,083.

To all whom it may concern:

Be it known that I, WILSON E. SYMONS, a citizen of the United States, residing at Chicago, in the county of Cook and State of Illinois, have invented a new and useful Steel Roof for Freight-Cars, of which the following is a specification.

The invention relates to a steel roof for freight cars.

10 The object of the present invention is to improve the construction of roofs for freight cars, and to provide a rigid watertight car roof of simple, efficient and comparatively inexpensive construction, capable 15 of obtaining sufficient support from the employment of a few carlines, and adapted to dispense with ridge pole purlins and a number of other features of old car roofs.

20 A further object of the invention is to provide a metallic car roof of this character, adapted to yield to the expansion and contraction due to variations in temperature, and capable also of yielding to torsional strains, vibrations and movements of a car 25 body, whereby injury to the roof from such sources is reduced to a minimum, and the durability or life of the car roof is materially increased.

Furthermore, the invention has for its object 30 to provide a car roof, equipped at the end portions of the car with doors, so that grain, coal or other commodities can be loaded through the roof and over the trucks, thereby not only facilitating the loading of 35 freight cars and the proper distribution of the load, but also obviating the necessity of shoveling the material after it has been loaded into the car, or shooting the material into the car with sufficient force to injure the 40 same.

With these and other objects in view, the invention consists in the construction and novel combination of parts hereinafter fully described, illustrated in the accompanying 45 drawings, and pointed out in the claims hereto appended; it being understood that various changes in the form, proportion, size and minor details of construction, within the scope of the claims, may be 50 resorted to without departing from the spirit or sacrificing any of the advantages of the invention.

In the drawings:—Figure 1 is a perspective view of a freight car, equipped with a 55 steel car roof, constructed in accordance

with this invention and illustrating the manner of loading the car through the roof. Fig. 2 is a plan view of the roof. Fig. 3 is an enlarged transverse sectional view. Fig. 4 is an enlarged sectional view, taken longitudinally of the roof through one of the doors thereof. Fig. 5 is an enlarged detail sectional view, also taken longitudinally of the car and illustrating the arrangement of the adjacent ends of the sections of the roof 60 and the running boards. Fig. 6 is an enlarged detail plan view of the door opening frame and the door guides. Fig. 7 is an enlarged transverse sectional view of the running boards, illustrating the manner of supporting the same. Fig. 8 is an enlarged detail sectional view, taken transversely of one of the running board supports. Fig. 9 is a detail perspective view of one of the running board supports, the nailing block 70 or piece being removed. Fig. 10 is an enlarged detail sectional view of one of the side edges of the roof, illustrating the manner of securing the same to a car body. Fig. 11 is an enlarged transverse sectional view 80 of the expansion joint. Fig. 12 is a longitudinal sectional view of one end of the expansion joint, the latter being equipped with an outside cap. Fig. 13 is a side elevation 85 of a portion of the car, showing one end of the expansion joint. Fig. 14 is a similar view, the expansion joint being equipped with an inside cap. Fig. 15 is a longitudinal sectional view of one end of the expansion 90 joint shown in Fig. 14. Fig. 16 is a detail 95 perspective view of the slide door. Figs. 17 and 18 are detail views of the combined lock and water shield. Fig. 19 is an enlarged detail sectional view, illustrating the manner of securing the carline to the sides of 95 the car. Fig. 20 is a detail perspective view of one of the carline supporting brackets. Fig. 21 is an enlarged detail plan view of the central longitudinal lap joint and the 100 expansion joint. Figs. 22 to 24 inclusive are enlarged detail sectional views, illustrating different forms of lap joints and carlines. Figs. 25 and 26 are detail views, showing different forms of lap joints.

Like numerals of reference designate corresponding parts in all the figures of the drawings.

In the embodiment of the invention illustrated in the accompanying drawings, the steel car roof is composed of two halves or 110

sections 1 and 2, connected at their adjacent transverse edges by an expansion joint 3, but for automobiles, furniture, or other extra long cars, the roof may be made in three or 5 more sections, connected together by extension joints, which permit the metallic roof to expand and contract through changes in temperature, and also to yield to the torsional strains, vibrations and movements of the car body, whereby injury to the roof is prevented.

Each section of the roof is preferably composed of sheets of steel of a size to extend from the side of a car body 4 to the center 15 thereof, and they are overlapped at their adjacent edges to provide transverse lap joints 5 and a central longitudinal butt joint 6. The lapped edges of the joints 5 are riveted together and are rendered water proof 20 by strips or layers 7 of tar paper, or other suitable material. Transversely disposed lap joints are preferably provided when channel carlines 8 and angle carlines 9 are employed for supporting the roof. When, 25 however, the carline consists of a T 10, a butt joint 11 is preferably employed. The adjacent edges of the roof sheets are covered and connected by a metallic welt strip 12 and a strip or layer 13 of tar paper, or other suitable 30 weather proofing material is interposed between the welt strip and the edges of the roof sheets to provide a water tight joint or connection. The members of the joint 11 are secured to the laterally extending flanges of 35 the T 10 by rivets 14, which pierce the carline 10, the roof sheets, the metallic welt strip, and the weather proofing strip.

The central longitudinal butt joint 6 is provided with a welt strip 15, and it has a 40 weather proofing strip 16 of tar paper, or other suitable material interposed between the welt strip and the adjacent longitudinal edges of the roof sheets. The members of the joint are secured together by rivets 17, 45 which pierce the roof sheets, the weather proofing sheet and the welt strip, as clearly shown in Fig. 7 of the drawings. When the sides of the roof slant from the center to the sides of the car, the welt strip will have a 50 slight angular bend at the center to form a ridge, as shown.

In applying the roof to the body of the car, the section 1 is first placed in position and the side and end edges are hammered 55 down over the upper edges of the fascia strip with a wooden mallet to avoid bruising or otherwise injuring the sheet steel, and the downwardly bent marginal edges 18 are secured to the fascia strip by suitable fastening devices. The side edges of the roof are 60 preferably provided with longitudinal slots 19, which receive nails 20, or other suitable fastening devices, and permit contraction and expansion of the roof in a longitudinal 65 direction. The slots are covered by narrow

metallic strips 21, as clearly illustrated in Fig. 13 of the drawings, and they extend from the ends of the car to the expansion joint 3.

The expansion joint 3, which is supported by one of the carlines 8, consists of a vertical flange 22, and a hollow arched rib 23, extending over the flange 22 and forming a covering or housing for the same, and provided at its outer or free side edge with a horizontal flange 24. The vertical flange 22 is formed integral with the section 1 of the roof, which is first placed in position and which is secured by rivets 25, or other suitable fastening devices to the carline 8. 70 The hollow rib, which is formed integral with the other section 2 of the roof, is provided at the top with a central straight or flattened portion 26, located above the flange 22 and being of a width to permit the necessary movement of the parts during the expansion and contraction of the joint. The members of the expansion joint have relative 75 slidable movement, and the arched hollow rib and the flange effectually exclude moisture and provide a water tight joint.

Instead of forming the hollow arched rib integral with one of the sections of the roof, both sections of the roof may be provided with vertical flanges 22^a, and the arched rib 95 may consist of a separate strip 26^a, secured to one of the roof sections and extending over both of the upright flanges, as clearly illustrated in Fig. 25 of the drawings. Also the expansion joint may consist of two 100 arched ribs 26^b and 26^c, as clearly illustrated in Fig. 26 of the drawings. The arched members of the joint overlap each other, and the inner arched member or rib 26^b is of a width less than the outer member or rib 26^c, so that the parts or members of the joint are permitted a relative slidable movement. The ends of the expansion joints are covered by caps 27, adapted to prevent rain from 105 beating in and entering the car and consisting of a vertical attaching flange or portion 28 and an arched top portion, conforming to the configuration of and fitting over the rib 23, as clearly shown in Figs. 12 and 13. The vertical attaching portion is secured by 110 nails 29, or other suitable fastening devices to the fascia strip. The vertical attaching portion of the cap may be fastened to one of the sections of the roof instead of to the side of the car if desired. Instead, however, of arranging the caps exteriorly of the rib 23, inside caps 30 may be employed. The 115 inside caps 30 are constructed similar to the caps 27, and the arched or transversely curved top portion fits within and conforms 120 to the configuration of the rib of the expansion joint. The rib of the expansion joint is provided at its ends with a depending approximately U-shaped flange 31, which fits 125 against the outer face of the vertical attach- 130

ing portion of the cap. The top portion of the cap extends over the vertical flange of the expansion joint, passing between the flange and the rib, as clearly shown in Fig. 15.

The arched rib of the expansion joint is capped at the center by means of an arched extension 32 of the welt strip 15, the strip 16 of tar paper or other weather proofing material being interposed between the arched portion 32 and the hollow rib of the expansion joint. The carline 8, which consists of metal channels, extends entirely across the car from one side to the other, and is provided with depending legs 33, supported by and interlocked with brackets 34. The legs are formed by bending the terminals of the carlines downward, and they are fitted against the side plates 35 of the car body. The carline supporting brackets are approximately U-shaped in horizontal section, and each is provided with an upper interlocking portion 35^a to fit within the channel carline 8, as clearly shown in Fig. 19 of the drawings, and it has a horizontal supporting ledge 36 upon which the leg 33 of the carline rests. The side flanges 37 of the upper interlocking portion 35^a of the bracket are arranged in the same vertical plane as and form continuations of the side flanges 38 of the bottom attaching portion of the bracket, and the side portions of the supporting shoulder 36 consist of exterior ribs 39, while the front of the interlocking upper portion of the bracket is inwardly off-set from the plane of the lower portion to form the front portion of the supporting shoulder 36. The bracket is secured to the side of the car by means of upper and lower bolts 40 and 41, the lower bolt pierces the lower attaching portion of the bracket and extends through the siding or sheathing, while the upper bolt 40 pierces both the upper attaching portion of the bracket and the leg 33^a of the carline 45 and extends through the side plate, the sheathing or siding, and the fascia strip of the car body. However, it will be readily understood that the improved roof may be applied with equal facility to car bodies of various structures, and the upper and lower bolts will extend through the side of the car body at the points where they pierce the bracket. The legs of the carline are maintained in their interlocked relation with the supporting brackets, and are securely fastened to the sides of the car by the upper bolts 40. The carlines may, as shown in Figs. 22 to 24 inclusive, consist of channels, angles, T's, and when angles or T's are employed the supporting brackets will be modified to conform to the configuration of the same.

The roof is equipped with running boards 42, composed of sections corresponding substantially to the roof sections and having

their adjacent ends located in close proximity to the expansion joint, as clearly illustrated in Fig. 5 of the drawings. The running boards which may be made of a single piece or of two or more sections, are mounted upon transverse supports, consisting of oblong metallic shells 43, open at the top to receive nailing blocks or pieces 44 and composed of side and end walls and a bottom 44^a, and provided with terminal attaching flanges 45, which are riveted or otherwise secured to the roof sections. The sides and ends are provided at the bottom with recesses or openings 46 and 47, and the nailing block or piece 44 is secured within the metallic shell or casing upon the bottom thereof by transverse fastening devices 48, which may consist of nails, as illustrated in Fig. 8 of the drawings. The side openings or recesses 46 are arranged at the center and end portions of the hollow shell, and the central recesses enable the support to span the central butt joint of the roof plates. The bottom 44^a is composed of bottom portions connecting the shell between the recesses or openings 46. The lower edges of the metallic shell are oppositely inclined to conform to the configuration of the inclined side portions of the roof. The nailing blocks or pieces 44 present horizontal upper supporting faces to the running boards 42, which are secured to the blocks or pieces 44 by nails 49, or other suitable fastening devices. Although three strips or supports 42 are shown, a single running board of the required width may of course be employed. The adjacent ends 50 and 51 of the sections of the running boards are arranged upon a transverse support 52, constructed similar to the support heretofore described, but having an increased width to permit the limited movement of the sections of the running board. The ends 50 of one section of the running boards are fixed to the support 52 by nails, or other suitable fastening means, and the terminal portions 51 of the other section of the running boards are free to slide upon the support 52. The ends 50 are connected with the roof section 2, which is provided with the hollow rib that is loosely arranged upon the section 1 of the car roof, and has a limited sliding movement thereon. Also by constructing the running boards in sections, one section may be removed with one of the sections of the roof without detaching the other sections of the running board.

No claim is made in the present application to the running board supports.

In order to facilitate the loading of freight cars and the distribution of the material over the trucks, the roof is provided at each end of the car with door openings 53, located at opposite sides of the running boards and surrounded by upwardly extend-

ing marginal flanges 54 of a door opening frame 55, but if desired the metal removed from the roof plates to form the door openings may be bent upward and constructed 5 to form integral upwardly extending flanges. The door opening frames are constructed of angle metal, which provides bottom attaching flanges, and the metal may be bent or formed into the shape of the door opening 10 in any suitable manner. Although a square door opening is illustrated in the accompanying drawings, any other form which will admit of a sliding opening movement may be employed. Strips 56 of tar paper, 15 or other water or weather proofing material are interposed between the attaching flanges and the roof plates, and are secured by rivets 57, or other suitable fastening devices, which fasten the door opening frames to the roof 20 sections.

The door openings are covered by sliding doors 58, constructed of sheet metal or other suitable material and provided at their side edges with depending inwardly extending 25 approximately L-shaped flanges 59, formed integral with the sliding doors and providing grooves to receive laterally projecting flanges 60 of angle guides 61, secured to the outer faces of the upwardly extending 30 side flanges of the door opening frames, and extending inwardly along the car a sufficient distance to support the sliding doors in their open position. The extended ends of the guide bars 61 are supported by L-shaped 35 plates 62, riveted to the roof plates and similarly secured to the adjacent ends of the guide bars. The inner or rear end of the sliding door is split at opposite sides and is bent downward to form a depending abutting 40 flange 63, which fits against the adjacent upwardly extending flange of the door opening frame, and the front end of the sliding door is equipped with a combined lock and water shield 64, consisting of a 45 strip of angle metal having one of its flanges fitted upon the upper face of the sliding door at the front end thereof, and hinged to the same by staples 65, or other suitable fastening means. The other flange 50 of the combined lock and water shield depends from the front edge of the sliding door and is adapted to fit against the front upwardly extending flange of the door opening frame, and it is provided at the center 55 with a slot 66 through which projects a horizontal staple 67. The staple 67 is mounted on the door opening frame, and it is adapted to receive an approximately L-shaped locking member 68, provided at one 60 end with a head and having a perforation at its other portion through which is passed the wire of an ordinary car seal 69, as clearly illustrated in Fig. 17 of the drawings, but any other form of sheathing or 65 locking device may be employed, as will be

readily understood. The sliding door may, however, be equipped with fibrous or other water proof material to provide a perfectly water tight connection when it is closed, but the depending guide and abutting flanges 70 and the depending flange of the combined lock and water shield are adapted to effectually exclude water from the interior of the car. By providing openings in the roof, grain, coal, or other commodities may be 75 loaded into the car through the roof, as clearly illustrated in Fig. 1 of the drawings, and the load will be distributed over the trucks, thereby obviating the necessity of shoveling the material by hand into the end portions of a car when the same is loaded through the side door. Also it dispenses with the necessity of shooting coal, or other material into the car with sufficient force to injure the same, as is frequently done when 80 it is attempted to load the car through the door-way and distribute the material over the trucks with the one operation.

Having thus fully described my invention, what I claim as new and desire to secure by Letters Patent, is:—

1. A metallic car roof including roof sections provided with an expansion joint having relatively movable overlapped portions, one of the portions being fixed and the other being formed with an arch to span the fixed portion and having its edge extended beyond the arch and supported by and slidably on the fixed portion, said arch being spaced from said fixed portion and having a limited sliding movement.

2. A metallic car roof including roof sections provided with an expansible joint composed of overlapped portions, one of the portions being fixed and provided with an upwardly extending flange and the other portion being arched to form a hollow rib to loosely receive the said flange, and provided at its free edge with an approximately horizontal flange extending beyond the arch and slidably supported by the said fixed portion beyond the upwardly extending flange thereof.

3. In a metallic roofing, the combination with a carline, of a fixed roof section supported by the carline and provided with an upwardly extending flange, fastening devices piercing the roof section and the carline and rigidly securing the former to the latter, and a relatively movable roof section also supported by the carline and bent to form a hollow rib to receive the upwardly extending flange of the first-mentioned section and supported by the latter beyond the said flange.

4. A metallic car roof including relatively movable roof sections and provided with an expansion joint having relatively movable members, a running board composed of sections mounted upon and secured

to the roof sections and having a joint arranged adjacent to the expansion joint and provided with relatively movable portions.

5. A metallic car roof including relatively movable sections provided with an expansion joint, one of the sections being fixed to the car at the said joint and the other section being free, a running board support secured to one of the roof sections, 10 and a sectional running board having a joint arranged upon the said support adjacent to the expansion joint of the roof, one of the sections of the running board being fixed to the support and the other being free.
- 15 6. A metallic car roof including relatively movable sections having overlapped portions forming an expansion joint, one of the sections being fixed to the car at the said joint, a support mounted on and secured to 20 the fixed section of the roof, a running board composed of sections corresponding with the sections of the roof and having their terminals arranged upon the said support, the running board section of the fixed roof section 25 being secured to the support and the other running board section being movable thereon.

7. A metallic car roof including a carline 30 constructed of channel metal and provided with a depending leg having spaced side flanges, and a supporting bracket provided with a supporting ledge receiving the leg and having an upper interlocking portion fitting between the said side flanges of the 35 leg.

8. A metallic car roof including a carline 40 constructed of channel metal and provided with a depending leg or portion fitted against the side of the car and having side flanges, and a supporting bracket provided 45 with a ledge or shoulder to receive the leg and having an inwardly off-set approximately U-shaped upper interlocking portion fitting between the side flanges of the depending leg or portion of the carline and holding the same against the car.

9. A metallic car roof including a carline 50 constructed of channel metal and provided with a depending leg or portion fitted against the side of the car and having side flanges, a supporting bracket U-shaped in horizontal section and having an interlock-

ing upper portion to fit within the depending leg or portion of the carline and off-set inwardly to form a supporting shoulder at 55 the front and provided at the sides with projecting horizontal ribs, and fastening devices piercing the bracket and the carline and securing the same to the car and maintaining them in their interlocked relation. 60

10. The combination with a car body, and a roof, of brackets arranged along the inner sides of the body below the roof, carlines extending transversely across the body and having their ends downturned and fitted to 65 the said bracket, the said car roof resting upon the carlines and secured to the same and lapped over the outside of the body at the top thereof, and bolts passing through the brackets, the downturned ends of the 70 carlines, the car body and the lapped portions of the roof.

11. The combination of a car body, a roof, a supporting bracket secured at its lower portion to the inner side of the car body 75 and having its upper portion offset from the body providing an intervening space and forming a supporting ledge at the bottom of the said space, and a carline supporting the roof and having a downturned end forming a leg and fitted in the space between the upper portion of the bracket and the car body and resting upon the said ledge. 80

12. A metallic car roof including roof sections provided with an expansible joint 85 composed of two overlapped portions, one of the portions being provided with an upwardly extending flange and the other portion being arched to form a hollow rib to span and loosely receive the said flange and provided at the outer side of the arch with an approximately horizontal flange extending beyond the arch and supported by the portion having the upwardly extending flange at a point beyond the latter, said portions 90 having relative movement, one being fixed 95 and slidably supporting the other.

In testimony, that I claim the foregoing as my own, I have hereto affixed my signature in the presence of two witnesses.

WILSON E. SYMONS.
